UNITED STATES PATENT OFFICE.

OSWALD S. PULLIAM, OF PITTSBURG, PENNSYLVANIA, ASSIGNOR TO PITTSBURGH EQUIPMENT COMPANY, OF PITTSBURG, PENNSYLVANIA, A CORPORATION OF PENNSYLVANIA.

SIDE-FRAME CONSTRUCTION.

No. 803,082.

Specification of Letters Patent.

Patented Jan. 5, 1909.

Application filed July 16, 1907. Serial No. 324,889.

To all whom it may concern:

Be it known that I, OSWALD S. PULLIAM, of Pittsburgh, in the county of Allegheny and State of Pennsylvania, have invented 5 certain new and useful improvements in Side-Frame Construction, of which the following is a specification.

This invention relates to improvements in side frame construction for cars and one 10 object of the present invention is to provide a new and improved construction whereby bolsters formed with column-guides may be readily placed in position in the bolster-receiving-openings of the side-frames and 15 removed therefrom.

Another object of my invention is to provide means for preventing the walls of the bolster-receiving-openings of the side-frames from being worn away.

20 A still further object of the present invention is to provide a separate and independent spring-seat.

With those ends in view my invention consists, of a side-frame construction, in the 25 novel features of construction, and in the combination of parts all as fully herein-after described and claimed.

In the accompanying drawing, which 30 illustrates applications of my invention, Figure 1 is a side elevational view partly in section of a side-frame construction embodying my invention; Fig. 2 a side elevational view of the same showing a modified form; Fig. 3 a sectional view taken on line 35 3—3 of Fig. 1; Fig. 4 a similar view taken on line 4—4 of Fig. 2; Fig. 5 a detail perspective view of spring-seat of the form of Fig. 1; and Fig. 6 a perspective view of one-half of the spring-seat of the form of Fig. 2.

40 Referring to the drawing, the side-frame proper 1 is formed with a bolster-receiving-opening 2. The opening 2 of each side-frame is adapted to receive an end of a bolster 3. The bolster illustrated is provided with a pair of column-guides 4 located on both sides of the bolster and near its respective ends. The bolster-receiving-openings are bounded by top and bottom flanges and by side flanges 5. In the form 45 of Fig. 2 the width of the opening 2 is substantially the same throughout its depth, the width being a little greater than the width of the bolster measured over its column-guides. By forming the opening of

the width mentioned the ends of the bolster 51 may be readily placed in position in said opening and removed therefrom.

In the form of Fig. 1, the opening is somewhat contracted at its upper portion, this is done to form fixed bolster-guides 6 60 adapted to engage the column-guides 4 of the bolster.

7 designates a spring-seat preferably comprising two upright-members 8 and a bottom-member 9. The spring-seat may be 65 either formed as an integral structure as clearly shown by Fig. 5, or it may be constructed of a plurality of parts as shown in the form of Fig. 2. The spring-seat in both forms is preferably a separate casting or 70 castings from the side-frame proper and in addition to serving as a seat for the springs 10, the upright-members thereof constitute fillers or removable bolster-guides and also provide means for protecting the side- 75 flanges 5 or the side-walls of the bolster-receiving-opening from contact with the bolster.

In the form of construction shown by Fig. 1, the upright-members 8 are secured 80 to the side-walls 5 by rivets 11. In the form of Fig. 2, the upright-members 8 are formed with flanges 12 adapted when in position to engage the edges of the side-walls 5 as clearly shown by Fig. 4. 85

What I claim is:

1. The combination with a bolster provided with column-guides, of a side-frame formed with a bolster-receiving-opening, a separable fixed spring-seat having an upright member or bolster-guide formed integral therewith, said bolster-guide located in the opening and extending upwardly to and between the column-guides of the bolster. 90

2. In a side-frame construction, the combination with a bolster provided with column-guides, of a side-frame proper having a bolster-receiving-opening, an independent fixed spring-seat comprising two parts each having a bolster-guide formed with means 95 for engaging a wall of the opening and extending upwardly to and between the column-guides of the bolster. 100

3. In a side-frame construction, the combination with a bolster provided with column-guides, of a side-frame proper having a bolster-receiving-opening, a separable fixed spring-seat formed with a bolster- 105

guide extending between the column-guides of the bolster, and means for securing the spring-seat to the side-frame.

4. In a side-frame construction, a side-frame proper having a bolster-receiving-opening, a separable fixed spring-seat having two upright-members extending upwardly to the bolster located in the bolster-receiving-opening on opposite sides of a bolster, and between the bolster and the side-walls of the opening.

5. In a side-frame construction, the combination with a bolster provided with column-guides, of a side-frame proper having a bolster-receiving-opening, a separable fixed spring-seat formed with an upright-member located in the opening and arranged in contact with the column-guides of the bolster.

6. The combination with a bolster provided with column-guides, of a side-frame formed with a bolster-receiving-opening

having a contracted upper portion and a lower widened portion, and an independent casting comprising a spring-seat and an up-standing member located in the widened portion and extending between the column-guides of the bolster.

7. The combination with a bolster provided with column-guides, of a side-frame formed with a bolster-receiving-opening having a contracted upper portion and a lower widened portion and an independent casting in the widened portion comprising a spring-seat and a pair of upstanding spaced members located in the widened portion.

In testimony whereof I affix my signature in presence of two witnesses.

OSWALD S. PULLIAM.
